UNITED STATES PATENT OFFICE.

HENRY F. CARRICO, OF PADUCAH, KENTUCKY.

WASHING-MACHINE.

SPECIFICATION forming part of Letters Patent No. 431,557, dated July 8, 1890.

Application filed March 15, 1890. Serial No. 343,998. (No model.)

To all whom it may concern:

Be it known that I, HENRY F. CARRICO, a citizen of the United States, residing at Paducah, in the county of McCracken and State 5 of Kentucky, have invented a new and useful Washing-Machine, of which the following is a specification.

This invention relates to washing-machines, more especially of that class in which an oscillating rubber rubs the clothes over a rough wash-board.

The object of the invention is to simplify the construction of washing-machines of this class heretofore made, and at the same time 15 to provide a machine in which the dasher or rubber is removable bodily for the insertion of the clothes, thereby doing away with the ordinary hinged cover heretofore employed. This object I accomplish by my improved 20 washing-machine, which consists, essentially, of a semicircular box having an internally-ribbed periphery and stationary portions at the ends of its top, an oscillating shaft mounted in semicircular bearings at the center of 25 the sides and in their upper edges, a removable top piece closing the otherwise open top of the box, and an operating-lever pivoted in standards on said top piece and carrying a toothed segment engaging a gear-wheel on 30 said shaft, the whole operating as hereinafter more fully described, and as illustrated in the accompanying drawings, in which—

Figure 1 is a side elevation of this machine complete. Fig. 2 is a central longitudinal 35 section thereof. Fig. 3 is a plan view with the top removed, and Fig. 4 is a bottom plan of said top.

The letter B designates a box of substantial semicircular shape, having its periphery 40 of corrugated galvanized iron forming a rubber or wash board W, all as is common in this class of machines. The top of this box is open at the center; but end pieces E securely close the ends of said top, as illustrated 45 in Fig. 3. The box is supported on suitable legs, as shown, and may be of any desired size and material preferred. At the center of each side piece of the box and in its upper edge is formed a semicircular bearing S, and 50 in these bearings are removably seated the reduced ends h of a shaft H. Pendent bars P

preferably extend downwardly from near each end of this shaft, and sliding loosely upon these bars, near their headed ends, is a dasher or rubber D, pressed normally downward by 55 the coiled springs C. The lower face of this dasher is provided with studs or spurs U, which take into the clothes being washed and prevent the dasher from slipping over them without rubbing them over the corrugated 60 bottom, all as will be clearly understood by a person familiar with this branch of the art.

The letter T designates the removable cover for the box B, which cover may be secured to the box proper by any suitable means, as buttons X. Rising from the upper face of this cover is a pair of standards s, between the upper ends of which is pivoted the operating-lever O, which has a toothed segment o at its lower end. The shaft H carries a gear-wheel 70 G, whose upper face stands normally above the upper edges of the sides of the box, and the cover T is provided with a hole t, through which this gear extends when the parts are assembled, whereby the segment and gear are 75 permitted to intermesh. A reciprocation of the operating-lever O therefore causes a simultaneous reciprocation or oscillation of the rubber D and effects the washing of the clothes.

When it is desired to insert the clothes to 80 be washed, the cover T is unfastened and removed, after which the shaft H, and with it the dasher D, is bodily removed from the box. Access can then be had to the latter through the opening in the top, as will be obvious. After the clothes are inserted the 85 shaft and cover are replaced, and the lever is reciprocated to wash the clothes, as above described. The clothes when washed are removed in the same manner.

Much difficulty has been heretofore experienced in machines of this character, owing to the cover leaking around the sides and ends of the box where the water is splashed up against it, and this difficulty I overcome 95 in the present instance by securely and irreversibly fastening the end portions E of the top of the sides of the box and having only the central portion thereof removable. The peculiar compound motion of the reciprocating mechanism also adds to the efficiency of 100 the machine, because it permits the pivot of

the dasher to be placed lower in the box, and therefore the latter can be made on a smaller circle than heretofore, and yet the same amount of power is imparted to the machine 5 as formerly.

I claim as the salient points of my invention—

1. In a washing-machine, the combination, with the box, a shaft pivoted in the sides 10 thereof, a dasher supported by said shaft, and a gear-wheel thereon, of the removable cover having a hole through which said gear projects, standards on said cover, and an operating-lever pivoted between said standards 15 and having a segment at its lower end meshing with said gear, as set forth.

2. In a washing-machine, the combination, with the semicircular box having corrugated bottom and ends, the vertical sides thereof 20 having semicircular bearings at their centers in their upper edges, and irremovable end pieces forming portions of the top, of a shaft having reduced ends journaled in said bearings, a dasher carried by said shaft and a 25 gear thereon, and a removable cover closely

fitting between said end pieces and provided with a hole through which said gear projects, standards on said cover, and an operating-lever pivoted between said standards and having a toothed segment at its lower end 30 engaging said gear, as set forth.

3. In a washing-machine, the combination, with the box having journals in its sides open at their upper ends and having stationary end pieces at its top, of the dasher-shaft 35 mounted in said journals and carrying a gear, the removable cover fitting between said ends and closing the open upper ends of said journals, an operating-lever pivoted in said cover and having a segment meshing with said gear, 40 and fastening devices for said cover, as set forth.

In testimony that I claim the foregoing as my own I have hereto affixed my signature in presence of two witnesses.

HENRY F. CARRICO.
